**BRACKET FOR ROTATABLE MOUNTING ON A
POST AND FOR SUPPORTING A PLURALITY OF
RADIAL ARMS**

John Rastocny, Cliffside Park, N.J., assignor to Diro
Industries Corp., Union City, N.J.

Filed Aug. 31, 1971, Ser. No. 176,775

Term of patent 14 years

Int. Cl. D8—08

U.S. Cl. D8—234

FIG. 1

FIG. 2

FIG. 3

FIG. 4

FIG. 5

FIG. 6

FIG. 1 is a perspective view of a bracket for rotatable mounting on a post and for supporting a plurality of radial arms showing my new design.

FIG. 2 is a top plan view thereof.

FIG. 3 is a side view thereof.

FIG. 4 is a perspective view of a modified form thereof.

FIG. 5 is a top plan view of said modified form.

FIG. 6 is a side elevation of said modified form.

The broken lines in FIG. 1, representing a fragment of a post rotatably supporting said bracket and a plurality of radial arms supported by said bracket, are shown for illustrative purposes only.

I claim:

The ornamental design for a bracket for rotatable mounting on a post and for supporting a plurality of radial arms, as shown and described.
